UNITED STATES PATENT OFFICE.

JOHN H. SATTLER, OF SAN FRANCISCO, CALIFORNIA, ASSIGNOR TO THE STEIGER & KEER STOVE & FOUNDRY CO., OF SAN FRANCISCO, CALIFORNIA, A CORPORATION OF CALIFORNIA.

GAS STOVE.

Application filed November 12, 1921. Serial No. 514,447.

To all whom it may concern:

Be it known that I, JOHN H. SATTLER, a citizen of the United States, and a resident of the city and county of San Francisco, State of California, have invented a certain new and useful Gas Stove, of which the following is a specification.

The invention relates to gas stoves provided with a solid fuel combustion chamber for the incineration of refuse or for the burning of solid fuel for house heating purposes.

An object of the invention is to provide a gas stove of the class described in which the gas oven is vented into the combustion chamber in such manner that products of combustion from the combustion chamber do not enter the gas oven.

Another object of the invention is to provide a gas stove in which the oven is efficiently, quickly and uniformly heated by the gas fire.

A further object of the invention is to provide a gas stove of the class described in which the products of combustion from the combustion chamber discharge directly into the exhaust flue and the products of combustion from the gas oven discharge indirectly into the exhaust flue.

The invention possesses other advantageous features, some of which, with the foregoing, will be set forth at length in the following description where I shall outline in full, that form of the invention which I have selected for illustration in the drawings accompanying and forming part of the present specification. In said drawings I have shown one form of stove embodying my invention, but it is to be understood that I do not limit myself to such form, since the invention, as set forth in the claims, may be embodied in a plurality of forms.

Referring to said drawings:

Figure 1 is a vertical longitudinal section of a stove embodying my invention.

Fig. 2 is a section taken on the line 2—2, Fig. 1.

Fig. 3 is a section taken on the line 3—3, Fig. 1.

Fig. 4 is a perspective view of the fire box side plate.

The stove of my invention is provided at one side, with a fire box 2, provided with a tiltable grate 3, for the burning of solid

fuel or refuse. The fire box is contained within a chamber formed by the front stove plate 4, the front oven plate 5, the top stove plate 6 and the bottom stove plate 7, upon which latter, the ash receptacle 8 is disposed. The side walls of the fire box are spaced from the front stove plate 4 and the front oven plate 5, forming passages between the fire-box and these plates and the upper edges of the side walls of the fire box 60 contact with the top stove plate 6. At the rear, the fire-box opens directly into the exhaust flue 9 and the exhaust products from the oven, pass into the fire-box and thence into the flue. 70

The gas oven is contained between the front oven plate 5, the back oven plate 12, the rear oven plate 13, the bottom oven plate 14 and the top oven plate 15. The bottom oven plate 14 is spaced above the 75 bottom stove plate 7 and a gas burner 16, extending longitudinally of the stove, is disposed in the space between said plates. Air for the combustion of the gas enters the burner chamber through a plurality of apertures 17 disposed in a longitudinal row adjacent the front edge of the plate 7. The bottom oven plate 14 is of less depth than the oven, providing a passage 18 at the rear thereof, for the passage of the hot gases 80 into the oven, and is of less width than the oven, being supported on angles 19 arranged at the front and back of the oven, providing passages 21, at the sides of the oven, for the passage of the hot gases from the burner 85 chamber into the oven. The hot gases from the burner chamber are also introduced into the oven through a row of apertures 22 in the bottom oven plate 14, adjacent the front edge thereof. The hot gases therefore enter 90 the oven at the front and rear and at the two sides and are uniformly and quickly distributed through the oven. The burner 16 is provided with an ignition tube 23 opening under one of the apertures 22, access to 100 which is obtained by opening the oven door 24. The oven is also provided adjacent the top with a broiling burner 25.

Disposed upon and spaced from the top oven plate 15, is a top plate 26, above which 105 the usual gas burners for frying and boiling are disposed. The chamber between the plates 15 and 26 is formed into a flue by the longitudinal partition 27, which extends from the front oven plate 5 toward the back 110

oven plate 12, but not to said latter plate. The exhaust products from the oven pass through the apertures 38, disposed in a row along the front edge of the top oven plate 5 and pass through the chamber or flue 28 and around the partition 27. From the chamber or flue 28, the exhaust products pass through apertures 31, in the front oven plate, behind the partition 27. The apertures 31 open 10 into the passage between the wall of the fire-box and the front oven plate. The wall 32 of the fire-box is bent inward at its upper edge 33 and along said bent-in portion, is provided with a row of apertures 34, 15 through which the exhaust products pass into the fire-box. The apertures 34 are positioned above the apertures 31, so that the hot exhaust products find a ready outlet and the products of combustion from the fire- 20 box do not pass into the chamber 28 or into the oven.

The flue 9 opens directly into the fire box 2, at the rear thereof, so that the gases of combustion pass directly from the fire box 25 into the flue. The gases of combustion produced by the combustion of gas, pass thru the aperture 38, around the partition 27, thru the apertures 31 and the apertures 34 into the upper portion of the fire box. 30 The heat generated by the combustion of material in the fire box is not employed to heat the oven and the gases of combustion of such materials pass directly thru the rear plate into the flue 9.

35 I claim:

1. In a gas stove, a top stove plate, oven plates enclosing an oven, a solid fuel combustion chamber disposed contiguous to one of said oven plates, said oven plate extending upward to said top plate, a fire box in said chamber spaced from said oven plate, the wall of said fire box adjacent said oven plate being provided with a plurality of apertures and said oven plate being provided 40 below said apertures, with a plurality of apertures for the passage of exhaust products from the oven.

2. In a gas stove, oven plates enclosing an oven, a solid fuel combustion chamber disposed contiguous to one of said oven plates, said oven plate being provided near its upper edge with apertures to permit the discharge of exhaust products from the oven into said chamber, a top stove plate closing 55 the top of said chamber, a fire box in said chamber having side walls extending into engagement with said top stove plate, the said wall adjacent the oven plate being provided with apertures for the passage of the exhaust products from the oven into the fire box and an exhaust flue connected to said fire box.

3. In a gas stove, a top stove plate, oven plates enclosing an oven, a solid fuel combustion chamber disposed contiguous to one of

said plates, said plate extending upward to the top stove plate and being provided with an aperture establishing communication between the combustion chamber and the oven, a fire box in said chamber having its wall 70 spaced from said oven plate and provided with an aperture above the level of said first aperture and a smoke flue directly connected to the rear of the fire box.

4. In a gas stove, a top stove plate, oven 75 plates enclosing an oven and including a front oven plate, a front stove plate extending upward to said top stove plate and co-operating with said front oven plate to form a combustion chamber, said front oven plate 80 being provided with apertures, a fire box in said chamber spaced from said front oven plate and provided on the side adjacent said front oven plate with apertures arranged above said first apertures, and a flue connected to said fire box.

5. In a gas stove, a front oven plate, a back oven plate, a rear oven plate, a bottom oven plate and a top oven plate, enclosing an oven, said bottom oven plate being spaced 90 from said rear, front and back oven plates and being provided adjacent its forward edge with a plurality of apertures, said top oven plate being provided adjacent its forward edge with a plurality of apertures and a gas burner disposed below said bottom oven plate.

6. In a gas stove, a front oven plate, a back oven plate, a rear oven plate, a bottom oven plate and a top oven plate, enclosing 100 an oven, said bottom oven plate being spaced from said rear, front and back oven plates and being provided adjacent its forward edge with a plurality of apertures, said top oven plate being provided adjacent its forward edge with a plurality of apertures, a gas burner disposed below said bottom oven plate, and a gas burner disposed in the oven adjacent said top oven plate.

7. In a gas stove, a front oven plate, a back oven plate, a rear oven plate, a bottom oven plate and a top oven plate, enclosing 110 an oven, said bottom oven plate being spaced from said rear, front and back oven plates and being provided adjacent its forward edge with a plurality of apertures, a gas burner disposed below said bottom oven plate, said top oven plate being provided adjacent its forward edge with a plurality of apertures, a top stove plate overlying and spaced from said top oven plate and forming therewith a chamber, a solid fuel combustion chamber, an exhaust flue opening directly into said combustion chamber, said front oven plate being provided with apertures connecting said chamber which lies above the top oven plate with the combustion chamber, and a gas burner disposed below said bottom oven plate.

8. In a gas stove, a front oven plate, a 115

back oven plate, a rear oven plate, a bottom oven plate and a top oven plate, enclosing an oven, said bottom oven plate being spaced from said rear, front and back oven plates and being provided adjacent its forward edge with a plurality of apertures, a gas burner disposed below said bottom oven plate, said top plate being provided adjacent its forward edge with a plurality of apertures, a top stove plate overlying and spaced from said top oven plate and forming therewith a chamber, a partition in said chamber extending from the front oven plate, said front oven plate being provided behind said partition with apertures opening into said chamber and a gas burner disposed below said bottom oven plate. 15

In testimony whereof, I have hereunto set my hand.

JOHN H. SATTLER.
